ARCH SUPPORT FOR SHOES

Filed July 1, 1929

By James J. Sheehy, Co.

Attorneys

UNITED STATES PATENT OFFICE

WINSLOW P. BRADFORD, OF BUFFALO, NEW YORK

ARCH SUPPORT FOR SHOES

Application filed July 1, 1929. Serial No. 375,268.

My present invention pertains to arch supports and it contemplates the provision of a shank that is adapted to be secured in a shoe through the medium of which a rigid support is provided for the tarsal bones of the foot while a flexible support is provided for the metatarsal bones.

The invention further contemplates the provision in an arch support formed with a shank so constructed and arranged that it extends well back under the heel of a shoe whereby fastening means may be employed to secure the inner sole, shank of the arch support, the outer sole and the heel together by the employment of one fastening means.

Other objects of the invention will be fully understood from the following description and claims when the same are read in connection with the drawings accompanying and forming part of this specification, in which:—

Figure 1 is a side elevation of the upper and heel of a shoe and showing in broken lines my novel arch supporting element.

Figure 2 is an inverted plan view of a shoe equipped with my novel device and showing the outer sole and heel removed from the shoe.

Figure 3 is a top plan view of the shank of the arch support and

Figure 4 is a perspective view thereof.

Similar numerals of reference designate corresponding parts in all the views of the drawings.

I illustrate a shoe having an upper 1 that is secured in the well known manner to the inner sole 2 and adapted to be secured on the shank of the inner sole, and to be invisible when the outer sole is secured in place, is a shank or arch support having the forwardly reaching rigid portion 3 that is adapted to support the tarsal bones of the foot adjacent the ball of the foot, and at a point slightly beyond the end of the support I provide the nibs 4 that are an integral part of the support and are punched therefrom. It will be seen that the portion 3 of the support lies practically flat against the inner sole 2 and is prevented from shifting by means of the nibs or brads 4 which take into the inner sole. The shank extends rearwardly from the end 3 and comprises the two forked portions 5 and

6. The portion 5 is curved slightly less than the portion 6 and when in position with respect to the inner and outer soles of the shoe as clearly illustrated in Figures 4 and 2 of the drawings, the portion 6' of the member 6 rests on the member 5. The purpose of this is to give resiliency to the shank when positioned. Otherwise if one shank portion did not bear on the other less support would be given to the shank of the shoe. It will be seen therefore that both stiffness and resiliency are present in my novel device. This device not only holds up the arch of the shoe but gives proper support to the tarsal and metatarsal bones of the foot and at the same time, the shank being flexible, exercises the muscles of the arch of the foot. Manifestly the ends of the members 5 and 6 are confined by the guides 7 and 8 which guides 7 and 8 are formed as an integral part of the member 9 of my novel support. This member 9 extends well back under the heel of the shoe and is secured to the inner sole by means of the two tacks 10 and is also provided with an elongated slot 11 that is adapted to engage or receive a screw or other fastening device 12. This screw 12 passes through the member 9 and secures the member to the inner sole and in turn engages the outer sole as well as the heel 13 together. It will be seen that any creeping of the support will take place during walking of the wearer and that a spring arch support is provided because notwithstanding the fact that the elements of the support are secured in the shoe nevertheless the manner of securing the portions 5 and 6 in the keepers 7 and 8 will permit slight backward and forward movement of the members 5 and 6 incident to movement of the wearer of the shoe. The shank may also be used to good advantage on all types of shoes made with leather or wooden heels, and the flexible fore part of the shank not only acts as a support but also tends to exercise the arch muscles and ease the metatarsal bones. Moreover it is so constructed that the various bends required for different types of arches of lasts are provided when spreading the wings at the time that they are stamped out. My device reduces the number of shanks re-

quired because it is adaptable to all shoes regardless of the height of the arch while the same rigid back portion is employed at all times.

5 It will be noted that the back element 9 is rigidly secured by the short tacks 10 to the insole and that the screw 12 of the heel 13 passes through an aperture in the back portion 9 of the support. This screw in conjunction with the tacks cause the back portion to be held rigid and support the scaphoid bone of the foot in the shoe. The slideable plate or the curved shank portions 5 and 6 thereof acts as a support for the metatarsal 15 bones of the foot while the flexibility of the support tends to develop the metatarsal muscles of the foot. Manifestly the fore part of the support will flex on movement of the foot in walking yet the construction of the 20 members 5 and 6 will tend to support the scaphoid bone during walking. It follows that the support as a whole acts as a rigid as well as a movable and flexible arch support.

25 What I claim is:—

1. An arch support comprising a shank portion, barbs formed on the shank portion; said shank portion comprising two wings one of which is curved slightly more than the 30 other and is adapted to bear on the first portion, and means secured to the heel portion of a shoe for confining the wings one against the other.

2. The combination of a single piece of 35 bendable material having a portion adapted to be secured on the inner sole of a shoe, wings formed in the material and so constructed and arranged that one of the wings laps over the other, and a member adapted to be secured 40 in the heel portion of a shoe and having guides to engage the wings of the first portion and further having an elongated slot to accommodate means for fastening a heel to the outer sole of the shoe.

45 3. An arch support comprising two members one of which is provided with wings so constructed and arranged that they lap each other and the other of which is provided with a body portion having an elongated slot therein, and means formed integral thereon for engaging the wings to permit flexible movement of the wings substantially as and for the purpose specified.

50 4. An arch support for shoes, comprising a rigid rear member having guides formed therein, rigidly supported to sustain the scaphoid bone, and a fore part comprising rearwardly extending flexible members one 55 of which is curved slightly more than the other and adapted to be engaged by the guides of the first portion; said forepart of the support being secured at one end to the inner sole and so constructed and arranged 60 that flexing of the foot will cause the rear-

wardly extending portions of the fore part to slightly flex.

In testimony whereof I have hereunto set my hand.
